UNITED STATES PATENT OFFICE.

WILLIAM SMITH, OF CHICAGO, ILLINOIS, ASSIGNEE TO UNIVERSAL ARCH COMPANY,
OF CHICAGO, ILLINOIS, A CORPORATION OF ILLINOIS.

LOCOMOTIVE ARCH-BRICK.

1,194,086.

Specification of Letters Patent.

Patented Aug. 8, 1916.

Application filed April 19, 1916. Serial No. 92,165.

To all whom it may concern:

Be it known that I, WILLIAM SMITH, a citizen of the United States, residing at Chicago, in the county of Cook and State 5 of Illinois, have invented certain new and useful Improvements in Locomotive Arch-Bricks, of which the following is a specification.

The present invention relates to the form, 10 of brick used in the fire-box of locomotives for providing a baffle or deflecting arch therein, and relates more particularly to the form and construction of the center brick of the sets of brick used in the above manner.

One object of the invention is to provide 15 a center brick which will be relatively light in weight, and at the same time will have sufficient body strength to withstand the strain it is subjected to in use.

A further object of the invention is to 20 utilize the ribs which strengthen the body portion as baffles on the under face of the bricks, to provide interruptions, which assist in the breaking up of the products of 25 combustion, thereby eliminating smoke.

A further object of the invention is to 30 provide spaces or openings between the under faces of the side edges of the bricks and the body of the tubes, upon which the 35 bricks are resting, thereby permitting a circulation or passage of heat clear around the tubes to insure an even distribution of heat throughout the entire area of the tube. The invention further consists in the features of 40 construction and combination of parts hereinafter described and claimed.

In the drawings: Figure 1 is a sectional view of a locomotive fire-box, with the 45 bricks of the present invention placed therein; Fig. 2, a sectional plan view through the fire-box, showing the bricks of the present invention therein; Fig. 3, a cross section on a somewhat enlarged scale, showing 50 a row of bricks resting upon the tubes and against the side wall of the fire-box; Fig. 4, a fragmental enlarged view of the parts shown in Fig. 3, showing one of the center bricks and one of the end bricks resting on tubes; Fig. 5, an enlarged side view 55 of two of the center bricks resting upon a tube; Fig. 6, an under face view of the center brick; Fig. 7, a front edge view of one of the center bricks; Fig. 8, a side edge view of one of the center bricks; and Fig. 9, a

perspective of one of the front or spacing 55; bricks.

In the art to which the present invention relates, there has developed a practice of placing a plurality of bricks upon the circulation tubes, which extend within and through the fire-box of a locomotive, thereby constituting a baffle or deflecting arch within said fire-box. These arches are made up of a plurality of bricks, each of a size to be inserted through and extracted from the interior of the fire-box, as is necessary to maintain a proper and complete baffle or arch therein. Necessarily, the weight of the bricks enters materially into the ease and quickness with which they may be inserted or removed, and it is desirable to make the bricks as light as possible, consistent with sufficient body strength to stand up under use.

In the present invention the major portion 75 of the bricks is made relatively thin and a strengthening rib placed on the under face, so as to make it sufficiently strong for use, and at the same time reduce the weight which would be present if the body 80 of the bricks throughout were made thick enough to be of sufficient practical strength. Also, these ribs are arranged and disposed in a manner so that they provide baffles or 85 interruptions on the under face of the bricks, which assist in breaking up the products of combustion and eliminating the smoke.

The bricks are so formed at their side edges, which rest upon the tubes, as to leave 90 a space or opening between the lower face of the brick and the tube, thus permitting a circulation of heat clear around the tube, so that the entire surface of the tube is 95 maintained in a uniform heated condition.

Referring now to the drawings, and particularly to Figs. 1 and 2, the invention is shown in conjunction with an inner fire-box section 10 and an outer fire-box 11. The inner section consists of an inner tube supporting wall 12, an outer wall 13, side walls 14, and a crown sheet 15; and the outer section 100 comprises an outer wall 16, a top wall 17, and a throat wall 18. The arrangement of these walls provides an outer water leg 105 19, side water legs 20, and a top water chamber 21; and the water legs 19 and 20 are closed by the usual mud rings 22.

All of the above is commonly and generally known in locomotive construction and no claim is made to the specific arrangement therein, since this may be changed without 5 affecting the spirit of the present invention.

Mounted within the walls 12 and 13 of the inner fire-box section are a plurality of downwardly inclined circulation tubes 23, upon which the bricks forming the arch or 10 baffle rest. The bricks consist of center bricks designated generally by the reference numeral 24, and end bricks designated generally by the reference numeral 25.

The end bricks are grooved at their inner 15 edges 27 to fit over the outer of the tubes 23, and are formed at their outer edge with a flat face 28, adapted to rest against the side sheet 14 of the inner fire-box section. This face 28 is so formed that when the brick is 20 placed diagonally, as shown in Figs. 3 and 4, the face 28 will rest against the side sheet with a full surface contact for its entire length. As shown in the drawings, these end bricks taper toward the outer end for 25 the purpose of reducing weight.

The center brick comprises a body portion formed on its under face with depending ribs or baffles 29. As will be seen from Fig. 6, these ribs extend diagonally from opposite 30 corners of the under face and intersect one another, so as to produce a rib of X-shaped formation on the under face. It is well known that a rib of this type is a very good mechanical construction for strengthening 35 purposes. Therefore, the body of the brick may be of relatively thin construction, since the rib will provide a reinforcement that will render the brick sufficiently strong for practical use. By making possible the em- 40 ployment of a relatively thin body, necessarily the brick is reduced in weight, so that the handling of it for the purpose of inserting into or removing from the fire-box is expedited; and also the amount of material 45 necessary to make the brick is reduced, cheapening the cost of construction. The strengthening ribs form baffles or interruptions along the under face of the bricks, which tends to break up the products of 50 combustion passing beneath the bricks, thus reducing smoke. As will be seen from the drawings, these center bricks have the side edges of their under face resting upon the circulation tubes, and for that purpose ribs 55 30 are formed, which extend inwardly from the termini of each of the ribs 29, and these ribs 30 are provided with grooves 31 adapted to receive the surface of the tube. The adjoining edges of these ribs 30 are spaced 60 apart somewhat thicker than the body portions, so that when the bricks are placed upon the tubes, there is an opening 32 provided between that portion of the body lying

between the adjoining ends of the ribs 30 and the outer periphery of the tubes, thus 65 permitting a circulation of heat clear around the tube. This is considered to be desirable because of the fact that if the bricks were made so that the upper portion of the tubes were entirely surrounded or inclosed by the 70 bricks resting thereon, the bricks, becoming heated, would necessarily maintain the upper part of the tube in a correspondingly heated condition. The lower portion of the tubes, being uninclosed by the bricks, would 75 be subjected to the changes in heat within the interior of the fire-box, which take place because of the frequent opening of the fire-box door. Thus, different portions of the tubes would be in different degrees of heat- 80 ed condition, which would cause a swelling or blistering of the tube along the lower edges of the bricks, thereby rendering the tubes liable to breakage. In the present invention this danger is eliminated by allowing 85 a passage of heat clear around the tubes, maintaining them in an even heated condition throughout their length. A front or spacing brick 33 is employed, which spaces the arch brick away from the wall 12 to permit 90 a circulation of heat through the fire-box. This latter, however, is well known in the art.

I claim:

1. A locomotive arch brick, comprising a 95 body formed with intersecting ribs on its under face extending from opposite corners of the bricks, and inwardly extending ribs running from the termini of the intersecting ribs, said inwardly extending ribs being 100 grooved to fit over a tube, and the adjacent edges of said inwardly extending ribs being spaced apart to provide a space between the body of the brick and the outer periphery of the tube to permit a circulation of heat completely around the tube, substantially as described.

2. A locomotive arch brick, comprising a body grooved along the under side edges to fit over a tube, and formed with intersecting 110 ribs on its under face constituting an X-shaped reinforcement for the body, and said ribs also furnishing a series of diagonally-extending baffle walls on the under face of the brick, substantially as described. 115

3. A locomotive arch brick, comprising a body grooved along its under side edges to fit over a tube, and formed with intersecting ribs on its under face to create an X-shaped reinforcement for the body, each rib being 120 V-shaped in cross-section, and said ribs combining to form a series of diagonally-sloping baffle walls on the under face of the brick, substantially as described.

WILLIAM SMITH.
